UNITED STATES PATENT OFFICE.

WILSON E. FACER, OF CLEVELAND, OHIO, ASSIGNOR, BY MESNE ASSIGNMENTS, TO THE FACER REFRIGERATING AND ICE MACHINE COMPANY, OF NEW YORK, N. Y.

REFRIGERATING APPARATUS.

SPECIFICATION forming part of Letters Patent No. 442,026, dated December 2, 1890.

Application filed December 6, 1888. Serial No. 292,862. (No model.)

To all whom it may concern:

Be it known that I, WILSON E. FACER, a citizen of the United States, residing at Cleveland, in the county of Cuyahoga and State of Ohio, have invented certain new and useful Improvements in Refrigerating Apparatus, of which the following is a full, clear, and exact description, reference being had to the accompanying drawings.

10 My invention relates to that class of refrigerating apparatus in which anhydrous ammonia or other equivalent refrigerant in a liquid state is forced into the refrigerating-pipes, where it volatilizes and absorbs the heat in so doing, the gas being afterward reconverted into a liquid state by mechanical compression and cooling without the employment of the commonly-used steps of collecting the gas in a liquid medium and then distilling it 20 out.

The parts of the apparatus herein shown and described relate to the mechanism which draws the volatilized refrigerant from the refrigerating-pipes, and thus reduces the pressure therein according to the continuity of its action, and thereby proportionately increases the rapidity of the volatilization and consequently the refrigerating effects of said volatilization, and to the mechanism which compresses the gas from the refrigerating-pipes, and thereby reduces it to a liquid and passes this liquid indirectly to the refrigerating-pipes, there to be again volatilized to produce refrigeration.

35 It also relates to the mechanism which moves as the pressure in said pipes varies and automatically controls the continuity of the action of the first-mentioned apparatus to the end of securing the proper rate of volatilization within said pipes for preserving an even temperature within the chamber being cooled thereby.

The apparatus in its entirety is a contrivance designed to produce low temperature within a certain confined space by the continual use of the same refrigerating medium—that is to say, by the continued volatilization and liquefaction of a given quantity of the refrigerating medium and to act automati-

cally to so govern the rate at which these changes in the condition of the medium occur that there shall be preserved within said space a substantially even temperature during an indefinite period.

Referring to the drawings, which show the best embodiment of my invention, Figure 1 is a side elevation. Fig. 2 is a top plan view. Fig. 3 is a longitudinal vertical sectional view. Fig. 4 is an end elevation, shown partly in section. Fig. 5 is a detached view of the devices by which the operative connection between the pump-operating mechanism and the power is made and broken as the pressure within the refrigerating-pipes varies. Fig. 6 is a detached view of another form of the devices for this purpose. Fig. 7 is a central sectional view of the oscillating shaft and its packing. Fig. 8 is a side elevation showing the whole refrigerating system.

Referring by letter to the parts shown in the drawings, A represents the lower part of a casing, and A' the upper part of the same. At the meeting edges of both the outwardly-projecting horizontal flanges *aa'* are formed, and the two parts A A' are fastened together, with a packing of rubber or other suitable material between their meeting faces, by means of bolts, which pass through said flanges, thereby forming a chamber A², into which the refrigerating medium is discharged from the refrigerating-pipes O. Between this chamber A² and the reservoir S is placed a gas-pump, by means of which the gas is pumped out of said chamber, condensed into a liquid form, and delivered into said reservoir S, from which it is delivered in a liquid state into the refrigerating-pipes O.

The specific form, arrangement, and mode of operation of the pump shown in the drawings are as follows:

In the bottom of the casing A two circular openings are formed, and two cylinders B B are fastened to the casing below said openings. Suitable packing of rubber or other material is interposed between the cylinders and the casing, and said cylinders are secured in place by bolts, which pass through the bottom of the casing and the flanges *bb* on the cylin-

ders. These cylinders are supported on a stand Z, which rests in a box Y, containing cold water, which rises nearly to the top of the cylinders and which is being constantly changed. In the lower part A of the casing a shaft C is suitably journaled, only one end of which extends through the side of said casing. The bearing for that end of the shaft which lies within the casing may be secured to the casing on the inside thereof, or it may be an integral part thereof; but for convenience and to reduce the cost of the casing casting an opening is made in the side of the casing, which is covered by a cylindrical flanged cap D, which, with suitable packing interposed, is bolted to the said casing, and the bearing for the shaft C is fashioned in said cap D. The other end of the shaft C extends through the casing and rests in a suitable bearing secured thereto. A flange or collar F is suitably secured to or made integral with the casing and surrounds said shaft on the inside thereof. In order that there shall be no escape of gas from the casing around the shaft, a rubber sleeve E is placed around said shaft, and this sleeve is fastened at one end to the shaft and at the other end to the collar F by suitable clamps—as, for example, the wires e, as shown. As a further improvement upon this means for preventing the escape of gas, and particularly to preserve the rubber sleeve, I first surround the shaft C with a coiled-wire spring H, which is fastened at its ends, respectively, to the shaft C and the collar F. The rubber sleeve fits over this coiled wire and is fastened beyond the ends of said coil to the shaft C and collar F, respectively, as described. This spring prevents the rubber sleeve from being forced by the pressure of the gas against the oscillating shaft C, and at the same time distributes evenly throughout said rubber sleeve the strain on the rubber caused by the oscillations of the shaft, and thereby prolongs the life and usefulness of the rubber sleeve. A walking-beam I is secured to the shaft C, and its ends are connected by suitable rods i i to the pistons J J of the pumps B. The piston-rods j j are guided in their movements by passing through ears j' j' on the casing and move freely through the slotted ends of the walking-beam I. Outside the casing the shaft C is provided with a crank-arm L, which is connected by a pitman c' to a wheel or crank k, attached to the shaft K, whereby the revolution of the shaft K gives to the shaft C an oscillating movement. The shaft K is journaled on top of the casing A'. Another shaft 10, similarly mounted, transmits motion to the shaft K through the gears h' h'. The shaft 10 is caused to revolve by suitable connections with any sort of power-supplying device, and provision is made, as hereinafter explained, by which the revolution of the shaft K may be stopped or started automatically by the varying action of the pressure within the re-

frigerating-pipes. The pump-pistons and cylinders may be of any well-known construction and are arranged to draw the gas from the chamber A² and to discharge it through suitable valved ports into a pipe N, which is coiled about the machine within the box Y, where it is submerged in the cold water, and finally connects with the reservoir or receiver S. This reservoir is of a common type, having an outlet-pipe, which extends to near the bottom, from which the liquid refrigerant is forced by the pressure of gas in the upper part of the reservoir. The gas which enters the pipe end is by compression and cooling reduced to a liquid state, and in this state is discharged into the reservoir. The liquid refrigerant is forced into the refrigerating-pipes through a suitable valve, which may be automatic or otherwise, whereby the rapidity of the flow is regulated. In the refrigerating-pipes O the refrigerant volatilizes, producing a reduction of temperature within the pipes and the chamber within which they are placed.

The amount of refrigeration produced by the volatilization of the liquid ammonia is greater the more rapid the volatilization. The volatilization is more rapid as the pressure of the gas within the refrigerating-pipes is reduced. In order, therefore, that the refrigerating effects of the apparatus shall be substantially equal at all times, I have arranged in connection with the devices above explained mechanism whereby the pressure of gas within the refrigerating-pipes is automatically controlled by the starting and the stopping of the pumping mechanism. I have found that when this pressure is between fifteen and twenty pounds the results are very satisfactory, and the mechanism which I shall presently describe is therefore preferably arranged to stop the pump when the pressure falls below fifteen pounds and to start it again when it is more than twenty pounds; but the mechanism is adapted to be adjusted so that the pump may be stopped and started at any predetermined degrees of pressure. The mechanism provided for this purpose consists of an elastic diaphragm so arranged that it will expand and contract under the influence of the gaseous pressure of the refrigerating-pipes O and devices which are operated by the movement of said diaphragm, by which the operative connection between the pump-operating mechanism and the power-supplying mechanism is made and broken automatically. The best form of this mechanism which I have devised is shown in the drawings, and I will now proceed to describe the same.

W represents a chamber, consisting of two elastic metallic diaphragms w w', which are bolted together with the metallic ring w² between them near their edges. This chamber is connected with the chamber A² by the pipe V, so that the pressure within the refrigerating-pipes, the chamber A², and the chamber W is the same. The central part of the diaphragm w' rests against the rigid bracket X,

whereby the diaphragm *w* is obliged to expand forward and away from the bracket under the influence of the internal pressure. A lever 1 is pivoted to the top of the casing and a set-screw 2 in the end of the lever 1 abuts against a button soldered or otherwise secured to the diaphragm *w*, whereby the outward movement of the diaphragm will move the lever 1 in one direction and the spring 3 draws it in the reverse direction when the pressure within the chamber *W* is reduced. A lever 4 is pivoted substantially at right angles to the lever 1 and has at its ends a roller or polished cylinder 5, which is held against the cylindrical end 6 of the lever 1 by a spring 7. Normally—that is to say, when the machine is at rest—the center of the roller 5 is a little above the center of the cylindrical end 6 of the lever 1, and thereby serves as a latch to prevent any movement of said lever 1. When the pressure within the chamber *A*² causes the diaphragm *w* to push the lever 1 outward, the movement thereof will be slow until the bearing-point of said lever passes a little above the center of rollers 5, when the spring 7 suddenly pulls the lever 4 under the lever 1. This throws the end of the lever 1 outward with a snap, and thereby brings into action the mechanism provided to drive the machinery of the pumps. This movement, as before stated, should take place when the pressure within the chamber *A*² is about twenty pounds. A gage 8 may be attached to the chamber *A*² to show the degree of pressure, and the set-screw 2 may be adjusted so that the above described motion will take place at any desired pressure. The mechanism provided for setting the machinery in motion may be some electrical contrivance, and the movement of the lever 1 may complete the electrical circuit, as shown in Fig. 6; or the movement of the lever 1 may throw clutch mechanism into engagement with a driven loose pulley 9 on the shaft 10, as shown in the first four figures. A clutch of any suitable construction may be employed, and the clutch may be operated by the movement of any ordinary shifting sleeve. A bar 12, having a depending fork 13, is arranged to slide parallel to the shaft 10 by being guided upon the caps of the journal-boxes of said shaft. This bar 12 obviously might be connected with the lever 1, but solely to increase its movement I add the lever 14, which is pivoted to the casing *A*, and link 15, which connects lever 1 and lever 14. The other end of the lever 14 is connected by a pin 16, operating in a slot 17, to the bar 12. When the pressure within the chamber *A* has been sufficiently reduced by the operation of the pumps, the return movement of lever 1 and the consequent disengagement of the operating mechanism are produced as follows: When the diaphragm begins to retract as the pressure within the chamber is reduced, the spring 3 draws the lever 1 backward. In this movement the locking-lever 4 is forced backward until the centers of the

two cylindrical bearing-surfaces 5 and 6 of the two levers pass, when the lever 1 is pulled quickly backward to the position shown in 7c the drawings, and the operative connection between the machine and the power-supplying mechanism is broken.

Having thus described my invention, what I claim as new, and desire to secure by Letters Patent, is—

1. In a refrigerating apparatus, the combination, with the refrigerating and condensing pipes or coils, the latter located and arranged within a tank, of a chamber with which the refrigerating pipes or coils communicate, and a pump or pumps projecting from said chamber into the cooling-tank and connected therein with the condensing-coils, substantially as herein shown and described. 85

2. In a refrigerating apparatus, the combination, with the refrigerating pipes or coils, of a chamber into which said pipes or coils discharge, a gas pump or pumps connected with said chamber and projecting into a cooling-tank, condensing pipes or coils located and arranged within said tank and connected with said gas-pump, and a reservoir between the refrigerating and condensing coils, substantially as shown and described. 90

3. In a refrigerating apparatus, the combination, with the refrigerating-pipes, of a chamber into which said pipes discharge, a reservoir and a gas-pump between said chamber and reservoir, an oscillating shaft within said chamber, one end thereof having a bearing within the chamber, the other end extending through the walls thereof and packed with a flexible packing, which is secured to said shaft and to the wall of the chamber, and suitable connections between said shaft and pumps for operating the latter, substantially as herein set forth and shown. 105

4. In a refrigerating apparatus, the combination, with the refrigerating-pipes, of a reservoir, a pump for pumping the gas from the pipes for condensing it and forcing it into the said reservoir, suitable mechanism for operating the pump, a chamber connected with the refrigerating-pipes, a flexible diaphragm arranged within a second chamber, communicating with the first, and adapted to be operated by the varying pressure of gas within said first chamber, and a lever adjustably held in engagement with said diaphragm and connected with a clutch mechanism, whereby the movement of said lever is caused to connect and disconnect the driving mechanism with and from the pump-operating mechanism, substantially as and for the purpose specified. 110 115 120 125

5. In a refrigerating apparatus, the combination of the refrigerating-pipes, a chamber into which said pipes discharge, a reservoir, a gas-pump by which the gas is pumped out of said chamber, condensed into liquid form, 130 and forced into the reservoir, and mechanism for operating said gas-pump, with an elastic diaphragm arranged to be operated upon by the pressure of gas within the refrigerating-

- 5 pipes, and mechanism operated by the movement of said diaphragm, whereby the operative connection between the pump-operating mechanism and the source of power is automatically made and broken at certain predetermined pressures within the refrigerating-pipes, substantially as and for the purpose specified.
6. In a refrigerating apparatus, the combination of the refrigerating-pipes, a chamber into which said pipes discharge, a reservoir, and a gas-pump between said chamber and fountain, with an elastic diaphragm arranged to be acted upon by the pressure within said chamber, a lever having one end made cylindrical, a set-screw in the other end, a spring for holding said set-screw in engagement with said diaphragm, a second spring-actuated lever having a curved end which engages with the curved end of the first-named lever, and mechanism whereby the operative connection between the pump and the power-supplying device is made and broken by the movement of the last-mentioned lever, substantially as and for the purpose specified.

7. In a refrigerating apparatus, the combination of the refrigerating-pipes, a chamber into which said pipes discharge, a reservoir, a gas-pump between said chamber and reservoir, a revolving shaft, suitable connecting mechanism between it and the pump, and a loose revolving pulley on said shaft, with clutch mechanism for connecting said pulley and shaft, a sliding bar adapted to engage and disengage said clutch, an elastic diaphragm arranged to be acted upon by the pressure within said chamber, a lever having one end made cylindrical, a set-screw in the other end, a spring for holding said set-screw in engagement with said diaphragm, a second spring-actuated lever having a curved end which engages with the curved end of the first-named lever, and suitable mechanism between the second lever and the sliding bar, substantially as and for the purpose specified.

WILSON E. FACER.
